UNITED STATES PATENT OFFICE.

FINLAY A. MCRAE, OF MONTREAL, QUEBEC, CANADA.

RAILWAY-CAR.

1,398,386.

Specification of Letters Patent. Patented Nov. 29, 1921.

Application filed May 13, 1921. Serial No. 469,368.

To all whom it may concern:

Be it known that I, FINLAY A. MCRAE, of the city of Montreal, Province of Quebec, Dominion of Canada, a subject of the King of Great Britain, have invented certain new and useful Improvements in Railway-Cars; and I do hereby declare that the following is a full, clear, and exact description thereof.

My invention relates to knock-down convertible cars and has for its object to provide a car of this type which may be utilized as a flat car or converted for use as a box car or stock car.

A further object of the invention is to provide a car of a simplified construction the body of which is composed almost entirely of sheet-metal and capable of being manufactured at minimum cost.

To this end my invention consists of the construction, combination and the particular arrangement of the parts hereinafter described and illustrated.

For full comprehension, however, reference must be had to the accompanying drawings in which similar reference characters indicate the same parts, and wherein:

Figure 1 is a side elevation of a car constructed according to my invention;

Fig. 2 is an end elevation thereof;

Fig. 3 is a plan view partly in horizontal section;

Fig. 4 is a fragmentary side elevation, partly in section the section being taken on line 4—4 Fig. 5;

Fig. 5 is a transverse sectional view taken on line 5—5 Fig. 4;

Fig. 6 is a detail fragmentary sectional view of the detachable connection between the adjoining edges of the side and end sections;

Fig. 7 is a detail sectional view taken on line 7—7 Fig. 4;

Fig. 8 is a detail sectional view taken on line 8—8 Fig. 1, and

Fig. 9 is a detail sectional view of the interlocking edges of the roof sections.

The car illustrated comprises a knock-down body and a sub-structure for supporting the same, the sub-structure being adapted to function as a flat car when the body is detached therefrom.

The sub-structure employed may be that illustrated in my prior United States Patent No. 1,236,195 granted August 7, 1917 and having dumping properties or as illustrated in the accompanying drawings it may

consist of the usual trucks 2, underframe including side sills 3 and end sills 4 and a floor 5^a permanently secured thereto. The knock-down body is constructed of sheet-metal sections detachably connected together. Each of the side walls is constituted by preferably two sections 5 and 6 each extending from one side of the door opening to the car end, such ends being constituted by unitary sheet metal sections 7 and 8.

The roof is detachably connected to the side and end walls and is constructed in preferably three sections, namely, end sections 9 united by an intermediate section 10 the latter being extended laterally as at 12 to overhang the door openings. The detachable connection between the sections 9 and 10 is effected by bending back the abutting edges in hook-form as at 13 and reinforcing them with rods 13^a around which the edges are bent, the bent-back edges of the end sections being turned upwardly and those of the intermediate section downwardly so that they may be detachably interlocked as indicated in Fig. 9.

The roof is detachably connected to the side and end walls by terminating the outer edges of the roof sections in depending flanges 14 which overlap the side and end sections and are bolted thereto as at 15, the bolts at the ends of the car also reinforcing the connection between the side walls and end walls.

This last mentioned connection is effected in a similar manner to that of the roof sections the vertical side edges of each end section overlapping the adjacent portions of the side sections and being bent back in hook form as at 16 and the adjacent edges of the side sections being also of a similar cross-section as indicated at 17, the hooked edges being in interlocking engagement. In order to clear the overlapping edges of the end sections, the flanges 14 on the roof are offset outwardly as at 18.

The body thus formed is reinforced by angle-irons, corner posts, side posts, end posts, diagonal end braces and horizontal end braces each of which is angular in cross-section. The corner posts 25 which are located within the body in position with their flanges in bearing relation with the adjacent side and end walls have their lower ends secured to the underframe by bolts 24 which are passed through inturned flanges

constituting integral parts of the lower ends of the posts; while the upper ends of the latter are secured to the adjacent roof, side and end sections by the bolts 15.

5 The side sections may be reinforced by any desired number of side posts arranged upon both inner and outer sides of the sections, those on the inside being indicated at 20 and those on the outside as at 21. As before mentioned these posts are constituted by angle irons and those on the inside extend from the roof to within close proximity to the car floor while those on the outside extend from the roof flanges 14 to the bottom edges of the side sections which latter like the end sections overlap the underframe and are bolted thereto as at 22.

The side posts are permanently riveted to their side sections as at 23^b and are so positioned on opposite sides of the sections that a member of substantially Z-cross section is obtained, each rivet assisting in holding an inner and outer post in place.

10 The inside posts adjacent the door opening indicated at 23 are of Z-cross section and perform the dual function of reinforcing the side sections and of acting as guides for vertically slideable flexible doors 24^a to be hereinafter described.

15 30 The posts reinforcing the end sections are indicated as follows: end posts at 25^b, diagonal braces 26 and horizontal end braces at 27. They are located on the outside and are permanently riveted to the end sections as at 28.

20 40 The doors 24^a are constructed of a multiplicity of metal slats connected together at their side edges and movable relatively to each other to impart flexibility. They are slideable in guideways 25^a from vertical positions closing the door openings to position one above the other immediately beneath the intermediate roof section 10. The guideways are provided by the vertical guides 23 and horizontal guides 26^a, the latter being secured to the end roof sections as at 27^a presenting double guideways to enable the positioning of the doors one above the other. The spaces between the ends of the guides 26^a and the car sides are closed by flanges 28^a formed upon the upper ends of the guides 23 as indicated in Fig. 7.

25 50 The bottom edge of each door is provided with an apron 29 which is offset outwardly as at 30 and adapted to extend below the floor level when the door is closed and overlaps an angular strip 31 extending across the bottom of the door opening and bolted to the underframe and side sections as at 32.

60 65 The side sections adjacent the top of each door opening are braced by a member 33 of angular cross-section bolted at its ends to the side sections as at 34 in position disposed transversely to the door opening and with one flange 35 parallel to and directly beneath

the overhanging portion 12 of the intermediate roof section being bolted thereto as at 36.

In order to provide auxiliary floor means which when not required may be converted into mangers when the car is being employed in the transportation of live stock, a second floor 37 is supported by the permanent floor 5. This second floor is divided longitudinally in the center line of the car throughout its length and transversely at adjacent each side of the door openings and midway the width of said openings into main and auxiliary sections. The former are indicated at 38 and are hinged at their longitudinal outer edges as at 39 being adapted to swing upwardly to positions disposed at an angle to the adjacent car sides and in conjunction therewith to present mangers for holding feed and the like. Any preferred means may be provided for maintaining the sections in manger position. In the embodiment illustrated hooks 33^a are provided and are carried by chains 34^a secured to the side walls of the body. The auxiliary sections are hinged to the main sections as at 35^a transversely to the length of the car and are adapted to be swung back thereupon to clear the door opening when such main sections are swung upwardly.

From the foregoing description it will be seen that my improved car may be so converted that it can be employed as a flat, gondola, box or stock car. When employed in the transportation of grain and the like it may be loaded through the roof by removing the bolts securing the intermediate roof section and sliding the latter out of engagement with the end roof sections. When loaded the roof section will be returned to its initial position bolted in place and sealed.

What I claim is as follows:

1. A railway car including a knock-down body having a door opening and roof detachably mounted thereon, said roof consisting of unitary sheet-metal end sections and an intermediate section the abutting edges of the sections being bent back in hook form and detachably interlocking, and the outer edges of the intermediate section being extended laterally to present portions overhanging the door opening.

2. A railway car comprising a flat car and a knock-down body and roof supported thereon, said body consisting of sheet-metal side sections and end sections, and the roof consisting of sheet metal end sections and an intermediate section, the outer edges of the end roof sections terminating in depending flanges adapted to overlap the adjacent side and end sections of the body and means detachably fastening the said flanges to the last mentioned sections, the abutting edges of the intermediate and end roof sections be-

- ing bent back in hook form and detachably interlocking and the outer edges of the intermediate section being extended laterally to present portions overhanging the door opening. 5
3. In a convertible railway car the combination with the side walls thereof and a fixed floor; of a second floor adapted to lie upon said fixed floor and including a plurality of sections hinged at their outer edges and adapted to be swung to positions in which in conjunction with the said side walls they constitute mangers, and means for maintaining the sections in said positions. 10
4. In a convertible railway car the combination with the side walls thereof and a fixed floor; of a second floor adapted to lie upon said fixed floor and including a plurality of sections hinged at their outer edges 20 and adapted to be swung to positions in which in conjunction with the said side walls they constitute mangers, and means for maintaining the sections in said positions, said second floor being divided longitudinally in 25 the center line of the car and transversely at points at each side of the door openings and midway the width of said openings into main sections and auxiliary sections, the main sections being hinged at their outer 30 edges and adapted to be swung to positions in which in conjunction with the side walls they constitute mangers, and the transverse abutting edges of the auxiliary sections and main sections being hinged together to enable 35 the former sections to be swung back upon the main sections when the latter are swung to manger forming positions; and means maintaining the main sections in said positions. 40
5. A railway car including a knock-down body having a door opening and roof detachably mounted thereon, said roof consisting of unitary sheet-metal end sections and an intermediate section the abutting 45 edges of the sections being bent back in hook form and detachably interlocking, and the outer edges of the intermediate section being extended laterally to present portions overhanging the door opening and means 50 reinforcing said overhanging portions. 55
6. A railway car including a knock-down body having a door opening and roof detachably mounted thereon, said roof consisting of unitary sheet-metal end sections and an intermediate section the abutting 60 edges of the sections being bent back in hook form and detachably interlocking, and the outer edges of the intermediate section being extended laterally to present portions overhanging the door opening and means for preventing displacement of the intermediate section transversely to the car. 65
7. A railway car including a knock-down body having a door opening and roof detachably mounted thereon, said roof con-
- sisting of unitary sheet-metal end sections and an intermediate section the abutting edges of the sections being bent back in hook form and detachably interlocking, and the outer edges of the intermediate section being extended laterally to present portions overhanging the door opening and means for preventing displacement of the intermediate section transversely to the car; said last mentioned means consisting of a member of angular cross-section secured to the body across the top of each door opening and having one flange disposed parallel to the adjacent overhanging roof portion, and means for detachably fastening said flange and roof portion together. 70
8. A railway car comprising a flat car and a knock-down body and roof supported thereon, said body consisting of sheet-metal side sections and end sections, and the roof consisting of sheet-metal end sections and an intermediate section, the outer edges of the end roof sections terminating in depending flanges adapted to overlap the adjacent side and end sections of the body and means 85 detachably fastening the said flanges to the last-mentioned sections, the abutting edges of the intermediate and end roof sections being bent back in hook form and detachably interlocking, and the outer edges 90 of the intermediate section being extended laterally to present portions overhanging the door opening, and combined means for preventing displacement of the intermediate roof section transversely to the car and for 95 bracing the said side sections. 100
9. A railway car comprising a flat car and a knock-down body and roof supported thereon, said body consisting of sheet-metal side sections and end sections, and the roof consisting of sheet-metal end sections and an intermediate section, the outer edges of the end roof sections terminating in depending flanges adapted to overlap the adjacent side and end sections of the body and means 105 detachably fastening the said flanges to the last-mentioned sections, the abutting edges of the intermediate and end roof sections being bent back in hook form and detachably interlocking, and the outer edges of the 110 intermediate section being extended laterally to present portions overhanging the door opening, and combined means for preventing displacement of the intermediate roof section transversely to the car and for 115 bracing the said side sections, said last mentioned means consisting of a member of angular cross-section secured to the side sections across the top of each door opening and having one flange disposed parallel to the adjacent overhanging roof portion, and means for detachably fastening said flange and roof portion together. 120
10. In a railway car the combination with sheet-metal knock-down body having a door 125

opening and a roof detachably mounted thereon, said body including side sections and members extending across the door openings at the top and bottom thereof, and 5 bracing the side sections, of a flexible vertical slideable door for closing each of said openings, the bottom edge of each door having an apron of Z cross-section adapted to overlap the lower of said members bracing

the adjacent side sections when the door is 10 closed.

In testimony whereof I have signed my name to this specification in the presence of two witnesses.

FINLAY A. MCRAE.
